CONTROL MECHANISM

Walter H. Smith, Wilkinsburg, Pa., assignor to
 Westinghouse Electric & Manufacturing Com-
 pany, East Pittsburgh, Pa., a corporation of
 Pennsylvania

Application November 12, 1938, Serial No. 239,931

14 Claims. (Cl. 171—313)

My invention relates to control mechanism and it has particular relation to reverse-direction-responsive controlling mechanism associated with a direct-current dynamo-electric machine and a storage battery on a railroad-car or other transportation-device. More specifically, my invention relates to apparatus for conditioning the air in passenger vehicles or for cooling commodities in other vehicles, particularly vehicles of the railroad type, although my invention is not limited to such uses.

One object of my invention relates to the provision of a so-called drag-relay characterized by having two pairs of contact-members, for each direction of movement, the contact-members of each pair being actuatable in responsive to different amounts of displacement of the drag-relay.

A further object of my invention relates to the provision of a distance-responsive relay comprising a pair of cam-actuated pivoted arms, with suitable means for holding and releasing the arms.

With the foregoing and other objects in view, my invention consists in the methods, systems, combinations and apparatus hereinafter described and claimed, and illustrated in the accompanying drawing, in which the single figure is a diagrammatic view of circuits and apparatus embodying my invention and illustrating the principles thereof.

The drawing shows my control mechanism in a form adapted for application to a railroad car having a car-axle 1 which is provided with a gear-drive 2 for driving an axle-driven shaft 3. The illustrated mechanism is utilized in connection with a refrigerating mechanism which is represented by a compressor 4 having a discharge-pipe 5 and a suction-pipe 6 for a refrigerant. The discharge and suction pipes 5 and 6 of the compressor 4 are connected by an unloader-valve 7 which is operated by an unloader-relay 8 in such manner that the compressor is unloaded when the unloader-relay 8 is deenergized, and so that the compressor is loaded, by closing the valve 7, when the unloader-relay 8 is energized.

The illustrated equipment also includes a storage battery 10 which is connected, through a switch 11, to positive and negative buses (+) and (-).

The equipment further includes a direct-current dynamo-electric machine 12 which is useable either as a generator for charging the battery 10, or as a battery-energized motor for driving the compressor 4 through a mechanical driving-

connection, such as the belts 13. The electric machine 12 is provided with a field-winding 14 and a commutating winding 15, the latter being connected in series with the armature-circuit 16, one terminal of which is permanently connected to the negative battery-terminal (-), and the other terminal of which is controlled in accordance with my invention.

10 The illustrated equipment further includes a speed-responsive, engageable and disengageable, mechanical driving-means, illustrated in the form of a centrifugal clutch 17, for mechanically connecting the axle-driven shaft 3 to the compressor 4 and to the electric machine 12 at car-speeds above a predetermined speed, such as 12 miles per hour, and for disconnecting the same at lower speeds.

15 In accordance with my invention, I provide a so-called drag-relay 18, and a so-called distance-relay 19, both of which are controlled, for convenience in installation, from an auxiliary shaft 21 which is mechanically connected, through a belt-drive 22, to the axle-driven shaft 3. Both the drag-relay 18 and the distance-relay 19 are of special construction, which will now be described.

20 The drag-relay 18 acts as a reversing-switch means for responding to movement of the car-axle 1, and it comprises a reversibly movable disc 23 or other switching member 23, having biasing means, in the form of two sets of springs 24 and 25, for restoring the disc 23 to a neutral central position. The biasing springs 24 and 25 are provided, as illustrated, with means, such as stops 26, for increasing the effectiveness of the springs 24 and 25 at a predetermined displacement of the disc 23 from its neutral position, in order to provide a first tilting-range in which the disc 23 is easily 25 tiltable, in either direction, and a second tilting-range in which it is necessary to exert a larger tilting-force per unit displacement of the disc 23.

25 The tiltable disc 23 of the drag-relay 18 carries four inclined mercury-switches 27, 28, 29 and 30, or equivalent tilt-responsive contact-mechanisms. These four mercury-switches 27 to 30 are arranged in pairs, one pair 27 and 28 being actuatable in response to forward movement of the car-axle 1, and the other pair 29 and 30 being actuatable in response to backward movement of the car-axle 1. The first mercury-switches 27 and 29 of the respective pairs are just slightly tilted, and thus they are arranged to be sensitively responsive to very slight displacements or tiltings of the switch-carrying disc 23,

and they are so arranged that their electrical contacts are broken when said mercury-switches 27 and 29 are actuated in response to the tilting of the disc 23. The second mercury-switches 28 and 30 of the respective pairs are tilted at a greater angle, so as to come within the second zone of operation of the biasing springs 24 and 25, and these second mercury-switches 28 and 30 are arranged to close their respective contacts when they are actuated in response to the tilting of the disc 23.

The tiltable switch-carrying disc 23 of the drag-relay 18 is actuated by means of a slip-permitting actuating means which is illustrated as a drag-disc 32 cooperating with a magnet 33. The magnet 33 is carried by the auxiliary shaft 21, while the drag-disc 32 is carried by a shaft 34 which is connected to the tilting disc 23. When torque is applied to the magnet 33, a very slight movement of the magnet with respect to its associated drag-disc 32 causes sufficient eddy currents in the drag-disc to establish a sensible torque in the shaft 34, tending to tilt the switch-carrying disc 23 in the same direction of rotation as the magnet 33. As the slip between the magnet 33 and the drag-disc 32 increases, the electrical torque also increases, up to a point determined by the design of the apparatus.

My distance-relay 19 is designed to detect movement in the auxiliary shaft 21 which, in turn, moves with the car-axle 1, and it comprises a pair of arms 36 and 37, pivoted at 38 and 39, normally drawn towards each other by means of a spring 41, and actuatable away from each other by means of a cam 42 carried by the auxiliary shaft 21. Each of the pivoted arms 36 and 37 carries two front or "make" contacts 43 and 44, and one back-contact 45, the make-contacts being closed when the respective arms are actuated, and the back-contacts being closed when the respective arms are in their normal non-actuated positions. The respective arms 36 and 37 are also provided with arm-holding means, illustrated in the form of magnet-coils 46, which are capable of retaining their respective arms in their actuated positions.

Associated with the steeply tilted mercury-switches 28 and 30 of the drag-relay 18, is a reversing relay 48 of a well known type, which is provided with a "forward" electromagnetic switching element 49 and a "backward" electromagnetic switching element 50, the two switching elements being mechanically connected together by means of a tilting lever 51, so that when one of the switching elements is closed, the other is open. The operating coil of the "forward" switching element 49 is energized by the closure of the "forward" mercury-switch 28, while the operating coil of the "backward" switching element 50 is energized when the "backward" mercury-switch 30 is actuated to close its contacts.

The reversing-switch elements 49 and 50 are each provided with a first make-contact 53 which serves to connect a control-circuit bus 54 to the positive battery-terminal (+) when either one of the steeply tilted mercury-switches 28 or 30 is actuated to its closed position.

Each of the reversing-switch elements 49 and 50 is also provided with a second make-contact 55 for connecting the negative battery-terminal (-) to either terminal 56 or 57 of the field-winding 14, depending upon the position of the reversing-switch mechanism 48. Each of the reversing-switch elements 49 and 50 is also provided

with a third make-contact 58 for connecting the second field-terminal 57 or 56 to a field-energizing circuit 59, depending upon the position of the reversing-switch mechanism 48.

The auxiliary switching bus 54 serves, among other things, to energize the operating coil of a so-called field-transfer switch 61, which is provided with a back-contact 62 and a front or make-contact 63. Thus, when the auxiliary re-laying bus 54 and the field-transfer relay 61 are deenergized, that is, when the steeply tilted mercury-switches 28 and 30 are in their non-actuated positions, the back-contact 62 of the field-transfer relay 61 is closed, so as to partially make a "motoring" field-energizing circuit which may be traced, for the present, from a conductor 64, through the back-contact 62, to two serially connected resistors 65 and 66, and thence to the field-energizing circuit 59. When the field-transfer switch 61 is energized, however, as a result of the actuation of either one of the mercury-switches 28 or 30, the "motoring" field-circuit is broken at the back-contact 62, while the make-contact 63 of the relay is closed, thus energizing a "generating" field-circuit extending from the positive battery-terminal (+), through a carbon-pile rheostatic voltage-regulator 67, and the make-contact 63, and thence to the field-energizing circuit 59.

The auxiliary control-circuit 54, which is energized from the positive bus (+) when either one of the steeply tilted mercury-switches 28 or 30 is actuated, is also utilized in the control of the generating operation of the electric machine 12, and for this purpose, it is connected in series with the usual "generating" contact 70 of a reverse-current relay 71, which may be of usual construction, and which is illustrated as having a polarizing winding 72 energized from the storage-battery terminals (+) and (-), and two actuating windings 73 and 74. The actuating winding 73 is a current-winding which is illustrated as being connected across a shunt 75 in the armature-circuit 16 of the dynamo-electric machine 12. The other actuating winding 74 is a voltage-winding which is connected so as to be responsive to the voltage-difference between the battery 10 and the armature-circuit 16 of the dynamo-electric machine 12, as will be subsequently described. In accordance with my invention, the reverse-current relay 71 is provided with an extra back-contact 78, which is not usually provided on such relays, but which I utilize as an extra safeguard in controlling the motoring operation of the electric machine 12, as will be subsequently described.

The first-mentioned make-contact 70 of the reverse-current relay 71 is utilized to connect the auxiliary switching bus 54 to a starting-bus 80 which is utilized for "starting" the dynamo-electric machine 12 in a manner which will be subsequently described. The "starting" circuit which traces back from the starting bus 80, through the reverse-current relay-contact 70, and the auxiliary switching bus 54, to one or the other of the steeply tilted mercury-switches 28 and 30, is utilized in controlling the operation of the dynamo-electric machine 12 as a generator.

I also provide means for controlling the "starting" circuit 80 during the operation of the dynamo-electric machine 12 as a motor, and this means will now be described.

The motoring operation of the dynamo-electric machine 12 is under the control of a circuit which starts to the left of the drag-relay 18, at

the positive battery-terminal (+), and thence passes through a thermostatic switch 81 to an auxiliary motoring circuit 82. The thermostatic switch 81 is utilized to close its contacts when it is desirable to operate the compressor 4 to produce more cooling, and to open its contacts when no more cooling is needed. The motoring circuit 82 is connected in series with the two back-contacts 45 of the distance-relay 19, and thence to an auxiliary motoring circuit 83. The two back-contacts 45 of the distance-relay 19 are connected in parallel with each other, so that the auxiliary motoring circuit 83 is energized whenever either one of the back-contacts 45 is closed, that is, whenever either one of the pivoted arms 36 and 37 is in its normal non-actuated position, provided, of course, that the thermostatic switch-contacts 81 are closed.

It is necessary, now to describe the connections of the distance-switch 19, whereby the opening and closing of the back-contacts 45 are controlled. Each of the holding-magnets 46, for holding the respective arms 36 and 37 in their actuated positions, is connected, through its associated front-contact 44, in an energizing circuit including a normally closed contact 84 of a thermal relay 85. The thermal relay 85 is provided with a heater-element 86 which is energized in series with both of the front-contacts 43, and in series with both of the slightly-tilted mercury switches 27 and 29 of the drag-relay 18, from the motoring circuit 82, which, in turn, is energized from the positive battery-terminal (+) through the thermostatic switch 81. The function of the thermal relay 85 is to introduce a time-delay of a predetermined amount, such as ten seconds, or, in general, some predetermined time, preferably a time-delay sufficient for the railroad-car to finish coming to a complete rest, after the tilttable switch-carrying disc 23 of the drag-relay returns to its normal neutral position, as the railroad-car approaches its condition of standstill after having been moving in either direction.

Picking up the thread of the motoring circuit which has been traced from the positive battery-terminal (+), through the thermostatic switch 81, the motoring circuit 82, and the distance-relay back-contacts 45, to the auxiliary motoring circuit 83, it will be noted that this auxiliary motoring circuit 83 is next connected in series with a make-contact 88 of a low-voltage cut-out relay 89, and thence through the "motoring" back-contacts 78 of the reverse-current relay 11, to the previously-mentioned "starting" circuit 80. The low-voltage cut-out relay 89 will be subsequently described.

The "starting" circuit 80, when energized either through the "generating" circuit starting with one or the other of the steeply tilted mercury-switches 28 or 30, or through the "motoring" circuit starting with the thermostatic switch 81, is utilized to energize a train of relays 91, 92, 93 and 94, which together constitute the starting mechanism for my dynamo-electric machine 12. The first relay 91 of this train is first energized from the "starting" circuit 80, through a back-contact 95 of the third relay 93. The first relay 91 thereupon instantly picks up and closes its make-contact 96 which instantly energizes the second relay 92, causing the latter to instantly pick-up and close its make-contacts 97 and 98, which instantly energize the third and fourth relays 93 and 94, respectively. The actuation of the third relay 93 closes its make-contact 100, 75

which energizes the main armature-circuit 16 of the dynamo-electric machine 12 by connecting the same in a circuit which is traced from the positive battery-terminal (+), through the starting relay-contact 100, thence through the shunt 75, and thence through a starting resistor 101, to the current-coil 102 of the rheostatic regulator 67, and thence through the commutating winding 15 to the armature of the dynamo-electric machine, the other terminal of which is permanently connected to the negative bus (-).

The first, second and fourth starting relays 91, 92 and 94 are of a type having an instantaneous pick-up and a slow drop-out of, say, two seconds, as is symbolized by the dashpots 104. The third starting relay 93 is the main line-contactor, having the main line-switch 100 as previously described, and it locks itself in, as indicated, through a holding-circuit make-contact 105, so that it thereafter stays "in" as long as the "starting" circuit 80 is energized, regardless of the position of the second starting relay 92.

The first and fourth starting relays 91 and 94 are provided with make-contacts 106 and 107, respectively, which are utilized to short-circuit the "motoring" field-resistors 65 and 66, respectively. The second starting relay 92 has a back-contact 108 which is utilized to short-circuit the armature-circuit starting-resistor 101.

As soon as the main line-contactor 93 picks up, it opens its back-contact 95 and deenergizes the first starting-relay 91, causing the latter to start to drop out in a time, such as two seconds, determined by its dashpot 104. When the first starting-relay 91 completes its drop-out movement, it opens its make-contacts 106 and 86, thereby inserting the field-resistance 65 in the "motoring" field-circuit, and deenergizing the second starting relay 92, causing the latter to start to drop out in a time, such as two seconds, determined by its dashpot 104. When the second starting-relay 92 completes its drop-out motion, it closes its back-contact 108 and opens its front-contact 98, thus cutting out the armature-circuit starting-resistance 101 and deenergizing the fourth starting relay 94, causing the latter to start to drop out in a time, such as two seconds, controlled by its dashpot 104. When the fourth starting relay 94 completes its drop-out movement, it opens its make-contact 107 and thereby inserts the field resistor 66 in the "motoring" field-circuit.

The voltage-coil 14 of the reverse-current relay 11 is connected across the main contact 100 of the main line-switch 93.

The carbon-pile voltage-regulator 67 which is utilized in the "generating" field-circuit is provided with a voltage-winding 110 which is responsive to the voltage of the dynamo-electric machine 12.

The unloader relay 8 which is associated with the compressor 4, is energized from the motoring circuit 82, which is energized whenever the thermostatic switch 81 is closed, calling for more cooling.

The low-voltage cut-out relay 89 comprises essentially a voltage-coil 112 which is normally connected in shunt across the battery terminals (+) and (-) through a resistor 113 and a make-contact 114 on the main line-contactor 93 of the "starting" mechanism. This low-voltage relay 89 also normally holds itself "in" through its own make-contact 115 which bypasses the make-contact 114 of the starting-relay 93. The function

of this low-voltage relay 89 is to drop out, opening the motoring control-circuit at 88, when the battery-voltage drops below a predetermined minimum value, corresponding, say, to a 70% condition of charge of the battery. The purpose of this safeguard is to prevent too great draining of the battery as a result of prolonged operation of the compressor 4 from the battery, the low-voltage cut-out relay 89 being provided in order to make sure that enough battery-capacity will always be left to take care of lighting, ventilating, and other necessary requirements.

In order to prevent the low-voltage cut-out relay 89 from dropping out, on the momentary dip in voltage resulting from the large current-inrush when starting the electric machine 12 as a motor, a weak series coil 116 is provided on the same magnetic circuit as the voltage-coil 112, and energized from the current-shunt 75, in such direction and amount, as to give the voltage-coil 112 a sufficient boost during the starting-current inrush when the motoring operation is first initiated.

In order to be able to start the compressor 4 when the car is standing in a switching yard, after a period of non-use with the main battery-switch 11 open, I have provided, in association with the resistor 113 of the cut-out relay 89, a starting push-button 118, which may be depressed, to pick up the cut-out relay 89, after 25 the main battery-switch 11 has been closed, if the battery-voltage is over 70% of its normal strength. The push-button 118 is preferably arranged to momentarily energize the cut-out relay 89 through only a portion of its series resistance 113. After the cut-out relay 89 has once picked up, it will seal itself in, through its make-contact 115, and its operating coil 112 will receive enough current, through all of the resistance 113, to hold the relay in its closed position.

The operation of the mechanism is as follows.

Referring to the generating operation of the electric machine 12, when the car starts into operation and attains a suitable speed for operating the compressor 4, such speed being perhaps of 45 the order of 12 miles per hour, the centrifugal switch 17 closes and mechanically connects the car-axle 1 to the electric machine 12 as well as to the compressor 4.

At any convenient speed between a very low 50 car-speed and the car-speed at which the reverse-current relay 71 picks up, so as to close its "generating" contact 70, the drag-relay disc 23 tilts far enough to close one or the other of the steeply tilted mercury-switches 28 or 30, depending upon the direction of the car-movement, thus setting up the field-reversing relay 48 in the proper polarity depending upon the direction of car-travel. For convenience in visualizing the phenomena, it may be assumed that the mercury-switch 28 or 30 closes when the car attains a speed of 12 miles per hour, the same as the operating speed for the centrifugal clutch 17, although these two operating speeds need not be identical with each other. When the mercury-switch 28 or 30 closes, it also energizes the field-transfer relay 61, thus braking the "motoring" field circuit at 62 and establishing a "generating" field circuit at 63, with maximum "generating" field-strength in the field circuit.

When the car attains a speed, such as 25 miles per hour, at which the generator-voltage is slightly in excess of the battery-voltage, the reverse-current relay-contact 70 closes, under the influence of its voltage-coil 74, thus instantly 75

energizing the starting relays 91 to 94, so that the main line-contactor starting-relay 93 will pick up and close its main-contact 100, completing the armature-circuit 16 of the generator, and 5 causing the generator to thereupon charge the storage battery 10. The reverse-current relay 71 then holds itself closed under the influence of its current-coil 73. It will be noted that the armature-resistance 101 is in circuit with the generator for a very brief time, until the second 10 starting-relay 92 drops out and closes its back-contact 108. When the car-speed drops back to a value below which the generator can no longer charge the battery 10, the reverse-current relay 15 71 drops out, opening its contact 70, thus de-energizing the main line-contactor 93, and opening the generator armature-circuit 16 at 100.

When the car is standing still, the dynamo-electric machine 12 is operable as a motor, driving the compressor 4 from the storage battery 10, under the control of the thermostatic switch 81. It will be remembered that the centrifugal clutch 17 is open, under these conditions, so that the mechanical driving-connection 13, which extends between the motor 12 and the compressor 4, is declutched from the axle-driven shaft 3.

When the car is standing still, the arm-holding magnets 46 of the distance-relay 19 are deenergized, so that the arm-biasing spring 41 is free to draw the pivoted arms 36 and 37 to their normal non-actuated positions, provided that the cam 42 is not in the way. The function of the cam 42, when it rotates, is to alternately actuate, or push out, first one and then the other of the pivoted arms 36 and 37, so that, at standstill, it is impossible for the cam 42 to be actuating, or pushing out, both of the pivoted arms 36 and 37. Hence, at standstill, at least one of the pivoted arms 36 or 37 is bound to be in its normal 40 non-actuated position, as controlled by the biasing spring 41, and it is possible that both of the pivoted arms 36 and 37 may be in their normal non-actuated positions, as illustrated.

Under the circumstances just described, the auxiliary motoring circuit 83 is energized, through one or both of the distance-relay contacts 45, and through the motoring circuit 82 which is under the direct control of the thermostatic switch 81. Since the low-voltage cut-out relay 89 is normally energized, its contact 88, in the motoring control circuit, is closed. Since the reverse-current switch 71 is in its deenergized position, its "motoring" contact 78 is also closed. An energizing circuit is thus completed from the auxiliary motoring circuit 83, through the contacts 88 and 78, to the "starting" control-circuit bus 80, which serves to start the motor by energizing (by way of relays 91 and 92) the main line-contactor 93, and completing the motoring circuit at the contact 100, thus connecting the motor armature-circuit 16 across the storage battery 10, in series with the starting armature-resistance 101.

The motor starts, with full "motoring" field-strength, through a portion of the motor-armature circuit 16, starting with the positive battery-terminal (+) at the main line-contactor relay-contact 100, and continuing on through the shunt 75 to the field-circuit conductor 64, and thence through the normally closed back-contact 62 of the field-transfer relay 61, and thence through the starting-relay contacts 106 and 107 which short-circuit the field-resistors 65 and 66. The field-circuit thereupon continues, through the conductor 59, and through

one of the contacts 58, the field-reversing relay 48, and through the terminals 56 and 57 of the field-winding 14, back to the negative bus (-) at one of the relay-contacts 55 of the field-reversing relay 48.

The motor 12 thus starts up, driving the compressor 4. At two-second intervals after the initial energization of the motor, the first, second and fourth starting switches 81, 82 and 84 drop out, thereby first cutting in the field-resistor 68, second cutting out the armature-resistor 101, and third cutting in the field-resistor 66, which places the field-circuit in its normal motoring condition.

The motor continues to operate, until the "starting" circuit 80 is interrupted, as at one of the contacts 81, 48 and 88.

When the car starts to move, the cam 42 of the distance-relay 18 immediately starts to move with the car-axle 1. The arm-holding magnets 48 of the distance-relay 18 are ready to be energized as soon as their respective associated make-contacts 44 are closed, the magnet-energizing circuit being completed through the normally closed back-contacts 84 of the thermal time-delay relay 85. The initial movement of the cam 42 thus results in actuating first one and then the other of the two pivoted arms 36 and 37, and each arm, as it reaches its actuated position, energizes its associated holding-magnet 48 and holds itself in its actuated position, so that the cam 42 will no longer strike that arm, as the cam continues to rotate. It will thus be evident that, before the cam 42 has made a complete rotation, both of the pivoted arms 36 and 37 will be locked in their actuated positions, with their back-contacts 48 open, so that the motoring control-circuit is opened at 48, even though the thermostatic switch 81 is closed, still calling for more cooling. It will be noted that this response of the distance-relay 18, in opening the motoring control-circuit at 48, will be made, at the earliest possible moment, in response to an extremely short distance of travel, and regardless of the speed of the car, which will be negligible at this point.

At the time when the back-contacts 48 of the distance-relay 18 open, the car may not have moved sufficiently to open either one of the slightly tilted mercury-switches 27 and 29 of the drag-relay disc 23, so that, if the thermostatic switch 81 still has its contacts closed, calling for cooling, a circuit will be completed from the positive battery-terminal (+), through the thermostatic switch 81, the mercury-switches 29 and 27, the two front-contacts 43 of the distance-relay 18, and the heating-element 86 of the thermal time-delay relay 85, as soon as both of the pivoted arms 36 and 37 are moved to their actuated positions. If this energization of the thermal time-delay relay 85 should continue for the ten seconds or other time necessary to effect the opening of the thermal relay-contacts 84, said contacts 84 would open, deenergizing the arm-holding magnets 48, and permitting one or both of the back-contacts 48 to reclose, thus restarting the motor 12.

It is impossible, however, for the thermal time-delay relay 85 to continue to be energized for anything approaching ten seconds, unless the railroad car immediately stops after the very slight motion necessary to open both contacts 48, because the slightly-tilted mercury-switch 27 or 29, depending upon the direction of rotation, is very sensitive in its response, and will respond

by moving to its actuated position, opening its contact, if the car continues to sensibly move, even at a very slow speed less than half of a mile per hour, after having moved far enough to open both back-contacts 48. As soon as one of the mercury-switches 27 or 29 opens, it deenergizes the thermal relay 85, thus preventing an opening of the thermal-relay contact 84, so that the arm-holding magnets 48 continue to remain energized, holding the pivoted arms 36 and 37 out of contact with the cam 42, as the latter continues to rotate with the rotation of the car-axle 1.

As the car continues to accelerate, it will finally reach the speed, such as 12 miles per hour, at which the centrifugal clutch 17 will engage, thus driving the compressor 4, and if the thermostatic switch 81 is still closed, calling for more cooling, the unloader relay 8 will be energized, thus causing the unloader-valve 7 to be in a closed position, shutting off the direct communication between the discharge-pipe 5 and the suction-pipe 6 of the compressor, so that the compressor will be loaded, performing the function of driving the refrigerant through the refrigerating equipment (not shown) which is connected to the pipes 5 and 6 in a manner which is readily understood.

If, while the centrifugal clutch 17 is engaged, the thermostatic switch 81 should open its contacts, signifying that no more cooling is needed, the unloader-relay 8 will be deenergized, causing the unloader-valve 7 to return to its normal open position, so that the refrigerant freely circulates through the valve 7, without sensible load upon the compressor 4, instead of passing through the refrigerating equipment as in the normal operation of the compressor.

When the speed of the car again drops below the operating point of the centrifugal switch 17, which may be something of the order of 12 miles per hour, the compressor 4 is again disengaged from the car-axle 1, so that it becomes, for the time being, impossible for the compressor 4 to be driven, so as to obtain cooling, even though the thermostatic switch 81 is closed, demanding more cooling.

When the car-speed reaches a very low value, which may be considerably less than one-half of a mile per hour, the drag-magnet disc 23 returns to its normal neutral position, so that both of the slightly tilted mercury-switches 27 and 29 are closed. A circuit will then be completed, assuming that the thermostatic switch 81 is still closed, through these two mercury-switches 27 and 29, and through the make-contacts 43 of the two pivoted arms 36 and 37 which are both being held in their actuated positions, so that the heating element 86 of the thermal time-delay relay 85 becomes energized. In a predetermined time thereafter, such as 10 seconds, depending upon the operating constants of the timing relay 85, the relay-contacts 84 open, thus deenergizing both of the holding-magnets 48, and permitting both of the pivoted arms 36 and 37 to return to their normal, non-actuated position, unless one of said arms may be held open by reason of the fact that the cam 42 might have come to rest underneath said arm. The timing-switch delay of 10 seconds is designed to be so long that, even though the car was slightly moving at the point when the drag-relay switches 27 and 29 were both closed, the car will have had more than ample time to come to a complete standstill, before either one or both of the pivoted arms 36

and 37 are permitted to return to their normal non-actuated positions in which they will close their back-contacts 48 and energize the auxiliary "motoring" control-circuit 83, provided that the thermostatic switch 81 is still calling for more cooling.

The time-delay of 10 seconds, more or less, introduced by the timing-relay 85, is particularly useful when the railroad-car is quickly brought to a stop, and instantly reversed, as frequently occurs when it is being driven by a switching engine. Under these circumstances, the 10-second time-delay prevents an undesired momentary starting of the electric machine 12 as a motor driving the compressor 4. If the motor had been permitted to momentarily start up, driving the compressor 4 in the same direction in which the car had first been travelling, which is the function of the field-reversing switch 48, then when the car suddenly reversed its direction of travel, and very quickly accelerated in the reverse direction, it might attain a speed of 12 miles per hour, sufficient to close the centrifugal clutch 17, before the compressor 4 had had time to come to a complete stop, thus subjecting the mechanical drive-mechanism to the strain of being required to first bring the compressor to standstill before it would be possible to start it up in the reverse direction.

It will be understood, of course, that any suitable braking means may be associated with the motor 12 for quickly stopping the same whenever it is electrically deenergized after a motoring operation. As such means are well known, I have not complicated my drawing by attempting to illustrate the same.

It will thus be seen that, between standstill and approximately 12 miles per hour of the railroad-car, or whatever other speed of operation is inherent in the speed-responsive clutch 17, it is impossible to obtain cooling, by means of the compressor 4. This is not a disadvantage, however, because passenger cars, and in general, other transportation-devices, do not operate, for any material length of time, at very low speeds. Thus, passenger trains commonly accelerate and decelerate at the rate of one mile per hour per second, so that the compressor 4 would be out of commission, on such a train, for a maximum period of 12 seconds, which would be altogether negligible.

I have shown an alternative connection, associated with the auxiliary "motoring" control-circuit 83, in the form of a two-position switch 121. In the full-line position of the switch 121, the "motoring" control-circuit connections are as previously indicated, with the "starting" bus 88 connected, through the relay-contacts 78 and 88, to the auxiliary motoring circuit 83, and thence through either back-contact 45 of the distance-relay 48, to the thermostatic switch 81. If this two-position switch 121 is moved to its dotted-line position, the "starting" circuit 88 is connected, through the relay-contacts 78 and 88 and the switch 121, to an auxiliary circuit 122, which is energized through the two slightly tilted mercury-switches 27 and 28, and thence to the thermostatic switch 81. Under these conditions, the starting and stopping of the motoring operation of the dynamo-electric machine 12 is directly under the control of the drag-relay mercury-switches 27 and 28; and the distance-relay 48 is not utilized at all. The operation of these mercury-switches 27 and 28 has already been fully described.

While I have illustrated my invention, and explained its mode of operation, in connection with a preferred form of embodiment, I desire it to be understood that such illustration and explanation are only by way of example, as many changes, in the way of omissions, additions, and substitutions, may be made by those skilled in the art without departing from all of the essential features of my invention. I desire, therefore, that the appended claims shall be accorded the broadest construction consistent with their language and the prior art.

I claim as my invention:

1. Mechanism for driving a mechanical load device on a movable transportation-device, comprising electrical driving-means for driving said mechanical load device when the transportation-device is stationary, mechanical driving-means motivated by the movement of the transportation-device for driving said mechanical load device when the transportation-device is moving, movement-responsive means responsive to a predetermined short distance of travel from standstill, substantially regardless of speed, for insuring a deenergization of the electrical driving-means when the transportation device begins to move, and time-delayed means, operative independently of the speed of the mechanical load device, for delayedly resetting said movement-responsive means to its non-responsive position after a cessation of movement of the transportation-device.

2. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, speed-responsive means responsive to the speed of the transportation-device, said speed-responsive means being operative in response to increasing speeds of the transportation-device for fulfilling a condition necessary to the functioning of the mechanical driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, means so interrelated to the decreasing-speed response of said speed-responsive means as to be operative only subsequently thereto in response to decreasing speeds of the transportation-device for fulfilling a condition necessary to the functioning of the electrical driving-means, movement-responsive means for insuring a deenergization of the electrical driving-means when the transportation-device barely begins to move, and time-delayed means, operative independently of the speed of the mechanical load device, for delayedly resetting said movement-responsive means to its non-responsive position after a cessation of movement of the transportation-device.

3. Mechanism for driving a mechanical load device on a movable transportation-device, comprising electrical driving-means for at times driving said mechanical load device, mechanical driving-means motivated by the movement of the transportation-device for at times driving said

mechanical load device, said electrical and mechanical driving-means being each effectively operative only upon the fulfillment of certain predetermined conditions, speed-responsive means responsive to the speed of the transportation-device, said speed-responsive means being operative in response to increasing speeds of the transportation-device for fulfilling a condition necessary to the functioning of the mechanical driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, means so interrelated to the decreasing-speed response of said speed-responsive means as to be operative only subsequently thereto in response to decreasing speeds of the transportation-device for fulfilling a condition necessary to the functioning of the electrical driving-means, movement-responsive means responsive to a predetermined short distance of travel from standstill, substantially regardless of speed, for insuring a deenergization of the electrical driving-means when the transportation-device begins to move.

4. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, speed-responsive means responsive to the speed of the transportation-device, said speed-responsive means being operative in response to increasing speeds of the transportation-device for fulfilling a condition necessary to the functioning of the mechanical driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, time-delayed means, operative independently of the speed of the mechanical load device, and delayedly resetting said movement-responsive means to its non-responsive position after a cessation of movement of the transportation-device.

5. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain

predetermined conditions, speed-responsive means responsive to the speed of the transportation-device, said speed-responsive means being operative in response to increasing speeds of the transportation-device for fulfilling a condition necessary to the functioning of the mechanical driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, time-delayed means, operative independently of the speed of the mechanical load device, and delayedly responsive to a substantially complete cessation of movement of the transportation-device for fulfilling a condition necessary to the functioning of the electrical driving-means, and means responsive to a predetermined short distance of travel from standstill, substantially regardless of speed, and cooperating with said time-delayed means, for insuring a deenergization of the electrical driving-means when the transportation-device begins to move.

6. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, speed-responsive means responsive to the speed of the transportation-device, said speed-responsive means being operative in response to increasing speeds of the transportation-device for fulfilling a condition necessary to the functioning of the mechanical driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, time-delay means responsive to a reduction of the speed of the transportation-device to a value below a predetermined low minimum for thereafter interposing a time-delay sufficient, in general, for the transportation-device to come to a complete rest, and for subsequently, after said time-delay, fulfilling a condition necessary to the functioning of the electrical driving-means, and means for insuring a deenergization of the electrical driving-means when the transportation-device begins to move.

7. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, speed-responsive means responsive to the speed of the transportation-device, said speed-responsive means being operative in response to increasing speeds of the transportation-device for fulfilling a condition necessary to the functioning of the mechanical

driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, time-delay means responsive to a reduction of the speed of the transportation-device to a value below a predetermined low minimum for thereafter interposing a time-delay sufficient, in general, for the transportation-device to come to a complete rest, and for subsequently, after said time-delay, fulfilling a condition necessary to the functioning of the electrical driving-means, and means responsive to a predetermined short distance of travel from standstill, substantially regardless of speed, for insuring a deenergization of the electrical driving-means when the transportation-device begins to move.

8. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, means operative at the first movement of the transportation-device, upon starting from standstill, for insuring a deenergization of the electrical driving-means when the transportation-device barely begins to move, time-delayed means, cooperative with said movement-responsive means substantially independently of the speed of the mechanical load device, and delayedly operative after the transportation-device has decelerated to a very low speed, for fulfilling a condition necessary to the functioning of the electrical driving-means, and means responsive to a materially higher speed of the transportation-device for fulfilling a condition necessary to the functioning of the mechanical driving-means in response to a transportation-device speed above said materially higher speed and for insuring that the aforesaid mechanical driving-means is substantially inoperative in response to a transportation-device speed below said materially higher speed.

9. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, means operative at a very low speed of the transportation-device, upon starting from standstill, for insuring a deenergization of the electrical driving-means when the transportation-device begins to move, time-delay means responsive to a reduction of the speed of the transportation-device to a value below a predetermined low minimum for thereafter interposing a time-delay sufficient, in general, for the transportation-device to come to a complete rest, and for subsequently, after said time-delay, fulfilling a condition necessary to the functioning of the electrical driving-means, and means responsive to a materially higher speed of the transportation-device for fulfilling a condition

necessary to the functioning of the mechanical driving-means in response to a transportation-device speed above said materially higher speed and for insuring that the aforesaid mechanical driving-means is substantially inoperative in response to a transportation-device speed below said materially higher speed.

10. Mechanism for driving a mechanical load device on a movable transportation-device, comprising electrical driving-means for driving said mechanical load device when the transportation-device is stationary, mechanical driving-means motivated by the movement of the transportation-device for driving said mechanical load device when the transportation-device is moving, a pair of pivoted arms, means for biasing said arms toward normal positions, means motivated by the initial movement of the transportation-device for alternately actuating said arms, one at a time, to their actuated positions, arm-holding means operative to retain each arm in its actuated position once it is actuated, and means for insuring the deenergization of the electrical driving-means when both of said arms are in their actuated positions at the same time.

11. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, and controlling-means for said electrical driving-means, comprising a pair of pivoted arms, means for biasing said arms toward normal positions, means motivated by the initial movement of the transportation-device for alternately actuating said arms, one at a time, to their actuated positions, arm-holding means operative to retain each arm in its actuated position, once it is actuated, time-delay means responsive to a reduction of the speed of the transportation-device to a value below a predetermined low minimum, and further responsive to both of said arms being in their actuated positions, for thereafter interposing a material time-delay and for subsequently, after said time-delay, releasing said arm-holding means, and means for fulfilling a condition necessary to the energization of the electrical driving-means in response to either one of said arms being in its normal non-actuated position, and for insuring the deenergization of the electrical driving-means in response to both of said arms being in their actuated positions.

12. Mechanism for driving a mechanical load device on a movable transportation-device, comprising a storage battery, a direct-current dynamo-electric machine operative either as a generator to charge said battery or as a motor energized therefrom, mechanical driving-means between said mechanical load device and said electric machine, speed-responsive engageable and disengageable mechanical driving-means motivated by the movement of the transportation-device for driving both the mechanical load device and the electric machine, reversibly movable reversing-switch means having biasing-means for restoring the same to a neutral central position, slip-permitting actuating-means motivated by the movement of the transportation-device in either direction for applying actuating-force to said reversing-switch means depending,

in direction and amount, upon the direction and speed of movement of the transportation-device, first and second forward-responsive contact-mechanisms actuatable at different forward displacements of said reversing-switch means, first and second backward-responsive contact-mechanisms actuatable at different backward displacements of said reversing-switch means, means for reversing the field of said dynamo-electric machine in accordance with which of said second contact-mechanisms was last actuated, reverse-current means for connecting and disconnecting said electric machine to and from the battery to control the generator-operation of said machine in accordance with its generated voltage, said second contact-mechanisms being actuatable at a speed of the translating device lower than the speed at which said reverse-current means operates, and motor-controlling means for controlling the connection of the electric machine to the battery for motoring operation in a predetermined manner responsive to a non-actuated condition of both of said first contact-mechanisms.

13. Mechanism for driving a mechanical load device on a movable transportation-device, comprising a storage battery, a direct-current dynamo-electric machine operative either as a generator to charge said battery or as a motor energized therefrom, mechanical driving-means between said mechanical load device and said electric machine, speed-responsive engageable and disengageable mechanical driving-means motivated by the movement of the transportation-device for driving both the mechanical load device and the electric machine, reversibly movable reversing-switch means having biasing-means for restoring the same to a neutral central position, slip-permitting actuating-means motivated by the movement of the transportation-device in either direction for applying actuating-force to said reversing-switch means depending, in direction and amount, upon the direction and speed of movement of the transportation-device, first and second forward-responsive contact-mechanisms actuatable at different forward displacements of said reversing-switch means, first and second backward-responsive contact-mechanisms actuatable at different backward displacements of said reversing-switch means, means for reversing the field of said dynamo-electric machine in accordance with which of said second contact-mechanisms was last actuated, reverse-current means for connecting and disconnecting said electric machine to and from the battery to control the generator-operation of said machine in accordance with its generated voltage, said second contact-mechanisms being actuatable at a speed of the translating device lower than the speed at which said reverse-current means operates, a pair of pivoted arms, means for biasing said arms toward normal positions, means motivated by the initial movement of the transportation-device for alternately actuating said arms, one at a time, to their actuated positions, arm-holding means operative to retain each arm in its actuated position, once it is actuated, time-delay means responsive to a

non-actuated condition of both of said first contact-mechanisms, and further responsive to both of said arms being in their actuated positions, for thereafter interposing a material time-delay and for subsequently, after said time-delay, releasing said arm-holding means, and means for fulfilling a condition necessary to the energization of the electric machine as a motor, in response to either one of said arms being in its normal non-actuated position, and for insuring the de-energization of the electric machine as a motor in response to both of said arms being in their actuated positions.

14. Mechanism for driving a mechanical load device on a movable transportation-device, comprising electrical driving-means for at times driving said mechanical load device, mechanical driving-means motivated by the movement of the transportation-device for at times driving said mechanical load device, said electrical and mechanical driving-means being each effectively operative only upon the fulfillment of certain predetermined conditions, speed-responsive means responsive to the speed of the transportation-device, said speed-responsive means being operative in response to increasing speeds of the transportation-device for fulfilling a condition necessary to the functioning of the mechanical driving-means in response to a transportation-device speed above a predetermined value, said speed-responsive means being operative in response to decreasing speeds of the transportation-device for insuring that the aforesaid mechanical driving-means is substantially inoperative in response to a transportation-device speed below a predetermined value, said electrical driving-means comprising a storage battery, a direct-current dynamo-electric machine, a double-duty main contactor-switch for connecting and disconnecting said dynamo-electric machine to and from the battery for both motoring and generating operation, mechanical driving-means motivated by the movement of the transportation-device for at times driving said dynamo-electric machine, a reverse-current switch for fulfilling a condition necessary to the closure of said main contactor-switch in response to an operational condition which qualifies the dynamo-electric machine to charge said battery and for effecting the opening of said main contactor-switch in response to an operational condition which disqualifies the dynamo-electric machine from charging said battery, means so interrelated to the decreasing-speed response of said speed-responsive means as to be operative only subsequently thereto in response to decreasing speeds of the transportation-device for fulfilling a condition necessary to the closure of said main contactor-switch, movement-responsive means for insuring an opening of said main contactor-switch when the transportation-device barely begins to move, and time-delayed means, operative independently of the speed of the mechanical load device, for delayedly resetting said movement-responsive means to its non-responsive position after a cessation of movement of the transportation-device.

WALTER H. SMITH.
